(57) **CLAIM**

We claim the ornamental design for individual shortening packs with container, as shown and described.

DESCRIPTION

FIG. 1 is an exploded perspective view of individual shortening packs with container showing our new design;
 FIG. 2 is a side elevational view thereof, the elevational view of the opposing side being identical thereto;
 FIG. 3 is a front elevational view thereof, the rear elevational view being identical thereto;
 FIG. 4 is a top plan view thereof; and,
 FIG. 5 is a bottom plan view thereof.
